tion of Illinois

Application May 29, 1948, Serial No. 29,962

5 Claims. (Cl. 123—41.38)

1

This invention relates to improvements in the cooling provisions for pistons of internal combustion engines, and the like.

It is a particularly important object of the present improvements to provide a simple and inexpensive member for directing a flow of cooling medium between and within the internal spaces and chambers of a piston, whereby to achieve a proper degree of turbulence in and velocity of the cooling medium across the zones of the piston subjected to the greatest temperature differential.

A more specific object of the invention is the provision of a piston body and connecting rod bearing carrier cooperatively formed and assembled to define a body crown or head chamber and a body skirt chamber, and the provision of chamber separating baffle means having a multiplicity of ports defined by angularly directed vanes such that the flow of a cooling medium between and in the chambers possesses both turbulence and velocity characteristics.

Other objects will appear from the following description relating to a presently preferred form of the invention, illustrated in the accompanying drawing, wherein:

Fig. 1 is a longitudinal sectional elevation through a piston assembly embodying present improvements;

Fig. 2 is transverse sectional view taken at line 2—2 in Fig. 1;

Fig. 3 is an enlarged and fragmentary sectional detail at line 3—3 of Fig. 2; and,

Fig. 4 is taken at line 4—4 of Fig. 3.

In the drawing, the piston assembly is characterized by a body 10 having an integrally formed crown 11 and skirt 12, a connecting rod bearing carrier 13, a connecting rod 14, and a baffle means 15.

The body 10 is provided with struts dependently formed at the under side of the crown 11. These struts are arranged in an inner series of circumferentially spaced, arcuately shaped elements 17 defining a central cavity 18 at the crown, and an outer series of circumferentially spaced, arcuately shaped elements 19 which are located between the inner elements 17 and the skirt wall of the body 10 to define an intermediate annular cavity 20 and an outer annular cavity 21. The strut elements 19 of the outer series are each connected with the skirt by a radially directed boss 22. The arrangement of these strut elements, there being shown in Fig. 2 four elements in each series, is intended to provide spaced and slot-like openings or ports be-

2

tween the center cavity 18 and the intermediate cavity 20, and similar ports between the intermediate cavity 20 and the outer cavity 21. These ports defined by each series of strut elements are staggered or out of registry whereby to create non-linear flow paths for a cooling medium. It is to be noted that the outer cavity 21 extends completely about the internal periphery of the crown 11 and above the boss elements 22 connecting with the outer struts 19.

The body 10 is further characterized by the provision of axially spaced and relatively thickened skirt wall bands 24 and 25, the band 24 being located near the crown end of the body and the band 25 near the bottom open end of the body. These thickened skirt wall bands provide for the formation of suitable annular grooves in which the usual rings may be seated. Additionally the upper band 24 is formed at its inner surface with an annular rib 26 which is machined to provide a cylindrical and shouldered seating surface 27 for engagement by the peripheral margin of the baffle means 15 (Fig. 3). During the machining of this annular seat 27, the several struts are also machined across their free ends to bring each thereof into endwise termination at a common transverse plane of the body 10. The lower thickened band 25 is internally formed to provide an axially directed, plain cylindrical surface 28 which is a bearing for the carrier 13.

The carrier 13 comprises an integral member having a flat upper face 30, an enlarged central section in which are formed the spaced bearing bosses 31, and a lower radially projecting flange 32 having a cylindrical margin 33 for a sliding fit at the plain cylindrical skirt surface 28. The bosses 31 are diametrically spaced to receive therebetween the upper apertured end 34 of the connecting rod 14. A wrist pin 35, and suitable bushing elements are disposed in and between the carrier bosses 31 and rod end 34 to connect the parts for operation, these parts being clearly indicated in Fig. 1. The carrier is also formed with a plurality (four being provided) of axially directed bosses 36 to receive an equal number of threaded studs 37. Each stud 37 engages in a threaded aperture of the bosses 22 and depends at the lower end of the carrier bosses 36 to receive a securing nut 38, whereby the carrier and body 10 may be firmly secured in assembly, as shown in Fig. 1, without restricting the skirt 12 against longitudinal movement relative to the flange 32 of the carrier 13 due to varying thermal conditions.

Prior to effecting the above described assembly, the baffle means 15 is positioned over the studs 31 and moved to its seat at the peripheral rib 26 and on the free ends of the struts 17 and 19. This baffle 15 is formed from flat plate or sheet material (Figs. 1 and 2) to have stud apertures 40 and a central enlarged aperture 41. When in position, the baffle means 15 is securely clamped at its central area between the struts 17 and 19 and the upper flat face 30 of the carrier 13. It is also peripherally clamped at four spaced zones between the lower face of each body stud boss 22 and the upper face of each carrier stud boss 36. The spaced peripheral zones of the baffle means 15 falling between the stud bosses are free above and below of any obstructing portions of the structure, and it is in these zones that there is provided a set of flow controlling vanes, each set of vanes having a plurality of flow directing vane elements, shown at 42 in Figs. 1 and 2, and more in detail in Figs. 3 and 4.

In Figs. 3 and 4, the plate 15 is suitable formed by a punching and shearing operation to provide radial vane elements 42 which are each turned to a suitable angle relative to the longitudinal axis of the piston body, or to the plane of the means 15, so that the adjacent vanes define an angulate port 43 opening at opposite faces of the plate means. Thus, fluid flow from one side to the other of the baffle will be confined to the four zones of the multiple vane elements 42, and in each such zone the angularly directed ports 43 will create high velocity streams along the adjacent wall of the piston skirt 12.

In Fig. 1, the location of the baffle means 15 clearly divides the interior spaces between the body 10 and insert 13 into a head end chamber 45 and a skirt end chamber 46. The supply of cooling fluid may be taken from the usual engine lubrication system (not shown) and the connecting rod 14 has an axial channel 47 acting to direct this fluid into the circumferential channel 48 formed in the wrist pin bore at its end 34 where it may flow under pressure about the wrist pin bushing to a top, radially directed port 49 opening toward the central crown cavity 18 defined by the inner series of struts 17. The central zone of the insert face 30 is suitably apertured at 50 to provide, with the central opening 41 in the baffle 15, an upwardly opening cavity above the top zone of the rod end 34. The cooling medium flowing into the crown chamber 45 of this assembly eventually passes through the angulate ports 43 to the skirt chamber 46 and is discharged to the crankcase by way of a port 51 in the bearing flange 32 of the insert 13.

When the piston is operating, the pressurized supply of cooling medium is dashed onto the central zone of the crown 11 in the cavity 18 and flows about the struts and through the several cavities formed in the head chamber 45 to the outer peripheral zones thereof. The inertia forces created due to reciprocatory motion of the piston causes the cooling medium to pass through the ports 43 at the vanes 42 to the annular skirt chamber 46 where a portion of the cooling medium may escape through port 51. A portion of the medium is retained in this skirt chamber 46 and during certain times in the cycle of operation, as the inward piston movement toward the crank end of the cylinder, the medium is caused to flow under inertia forces reversely through the vane ports 43 to the crown chamber 45. This reverse flow occurs at high velocity and is directed by the pitch of the vanes 42 in a spiral

path to create great turbulence in the chamber 45 and an intimate contact at the hottest zones of the crown 11 so that a maximum transfer of heat results. When the piston moves toward the 5 chamber end of the cylinder, this hot medium is dashed through the vane ports 43 to the skirt chamber 46. This cyclic dashing of the cooling medium between the crown and skirt chambers is superposed on the general trend of flow from the supply port 49 in the top zone of the connecting rod end 34 to the skirt outlet port 51. The beneficial results are that the fluid medium is retained in the piston sufficiently long to absorb and pick up a maximum of the heat imparted to the crown surfaces 11, and the fluid medium is forced to dash in and about the crown chamber 45 in intimate contact with the crown surfaces with a great degree of turbulence. Thus, the cooling medium is enabled to pick up heat at a rate which will maintain the piston crown 11 and adjacent surfaces at a temperature well within safe limits to insure long life and improved operation of the piston.

Having now described a preferred form of piston assembly embodying the cooling provision of improved character, it is to be understood that the invention may include other forms which come within the spirit and scope of the claims hereto appended.

What is claimed is:

1. In a piston assembly, the combination of a cylindrical piston body having a crown, a skirt, and strut means extending from the crown in a direction axially of the body, said body skirt having a straight cylindrical surface concentric with the body axis, an insert member formed with a flat upper face and a cylindrical bearing surface remote from the upper face, said insert being positionable in the body with its upper face opposed to said strut means, and having its remote cylindrical surface bearing at said straight cylindrical surface of the skirt to maintain the insert spaced from the crown and skirt and thereby provide crown and skirt chambers, the insert further providing an inlet opening in its upper face for supply of cooling medium to the crown chamber and a port adjacent its remote bearing surface for discharge of the cooling medium, and a baffle means disposed between the strut means and the upper face of the insert and arranged to separate the crown and skirt chambers, said baffle means having sets of vane elements defining ports for the control of the flow of cooling medium between said chambers during piston operation.

2. The combination as defined by claim 1, and in which said vane elements are arranged to cause a high velocity flow of the cooling medium under inertia forces imparted to the cooling medium during piston motion, and in which the 60 vane elements are angularly directed relative to the longitudinal piston axis to direct the flow of cooling medium angularly into each chamber.

3. The combination in a piston assembly of oil cooled type, of a piston body providing a skirt 65 and a crown formed with a plurality of depending strut elements, an insert member providing spaced bearing bosses and being formed with a flat face at one end and a radially directed flange at its opposite end, the flat face having 70 an opening therethrough and the flange having a port, means securing said insert to said body with its flat face adjacent said strut elements and the radial flange bearing against the skirt with a sliding fit to permit relative longitudinal expansion of the skirt, a connecting rod carried by

and between the insert bosses and providing flow means for directing a supply of cooling oil through the insert opening and against the central area of the crown, and baffle means secured between the insert face and the crown strut elements to project outwardly and separate the piston body interior into crown and skirt chambers, said baffle means providing vane elements defining ports which open between said chambers, the vane elements being angularly turned and closely spaced to effect the flow of high velocity streams of cooling oil to said chambers during the periodic acceleration and deceleration of the piston, the port in said insert flange serving to permit discharge of the cooling oil flowing into the skirt chamber.

4. In a piston assembly of fluid cooled character, the combination of a piston body having a crown and a skirt, an insert member secured within said body and formed with a bearing for a connecting rod, the body and insert being so spaced apart as to form a crown chamber and an annular skirt chamber through and between which cooling fluid is adapted to flow, and baffle means comprising a separate plate element secured within said body between said chambers, and providing a plurality of relatively spaced vanes directed at an angle to the plane of the plate element, said vanes forming flow controlling ports opening between said chambers to project the cooling fluid at high velocity therebetween under the influence of the inertia forces set up during piston operation.

5. In a piston assembly of fluid cooled character, the combination of a piston body having a crown and a skirt, an insert member secured within said body in spaced relation to the crown and skirt to form a crown chamber and an annular skirt chamber, and a baffle plate positioned between said body and insert member to separate said chambers, said baffle plate being formed with a plurality of sets of vane elements adjacent its periphery, the vane elements of each set being inclined with respect to the plane of the plate and defining ports therebetween for directing the flow of a cooling fluid between said chambers and for imparting high velocity to the cooling fluid as a result of the inertia forces incident to piston operation.
